(57) **CLAIM**

(73) Assignee: **Minolta Co., Ltd.**, Osaka (JP)

The ornamental design for a handle and front panel portion of a paper feed cassette, as shown and described.

(**) Term: **14 Years**

DESCRIPTION

(21) Appl. No.: **29/120,915**

FIG. 1 is a front perspective view of a handle and front panel portion of a paper feed cassette showing our new design; FIG. 2 is a top plan view thereof;

(22) Filed: **Mar. 29, 2000**

FIG. 3 is a front elevational view thereof;

(30) **Foreign Application Priority Data**

FIG. 4 is a rear elevational view thereof;

Sep. 29, 1999 (JP) 11-26396
Sep. 29, 1999 (JP) 11-26397

FIG. 5 is a right side elevational view thereof, the left side elevational view being a mirror image thereof;

(51) **LOC (7) Cl.** **16-03**

FIG. 6 is a bottom plan view thereof;

(52) **U.S. Cl.** **D18/40**

FIG. 7 is a cross-sectional view taken in the direction of line VII—VII shown in FIG. 3;

(58) **Field of Search** ..... D18/36—40; D8/315, D8/316; 16/110.1, 415; 399/1—7, 75, 411

FIG. 8 is a front perspective view of a handle and front panel portion of a paper feed cassette showing a further embodiment of our new design;

(56) **References Cited**

FIG. 9 is a front elevational view thereof;
